CLAIM

The ornamental design for a golf club head, as shown and described.

DESCRIPTION

FIG. 1 is a front elevational view of a golf club head;
FIG. 2 is an enlarged partial front view of the golf club head of FIG. 1;
FIG. 3 is a partial cross-sectional view thereof taken along the line 3—3 of FIGS. 1 and 2;
FIG. 4 is a perspective view thereof; and,
FIG. 5 is an enlarged partial perspective view of the golf club head of FIG. 4.
The broken lines showing various portions of the golf club head and scoreline pattern depict environmental subject matter only and form no part of the claimed design.
